(57) **CLAIM**

The ornamental design for a collapsible lantern, as shown and described.

DESCRIPTION

FIG. 1 is a perspective view of a collapsible lantern, showing my new design;

FIG. 2 is a front elevation view of FIG. 1, the rear elevation view being a mirror image thereof;

FIG. 3 is a left side elevation view of FIG. 1, the right side elevation view being a mirror image thereof;

FIG. 4 is a bottom plan view of FIG. 1;

FIG. 5 is a top plan view of FIG. 1; and,

FIG. 6 is a perspective view of FIG. 1, shown in a collapsed condition.

The broken lines shown in the drawings depict portions of the collapsible lantern that form no part of the claimed design.
